Term of patent 14 years

(Cl. D54—13)

FIG. 1

FIG. 2

FIG. 3

FIG. 1 is a front elevation of a pair of slip joint pliers embodying my new design;

FIG. 2 is a side elevation thereof;

FIG. 3 is a fragmentary perspective view showing the plier jaws in an open position.

The characteristic features of my design for the pliers disclosed reside in the handles having the pattern shown.

I claim:

The ornamental design for slip joint pliers, substan-
tially as shown and described.
